(57) **CLAIM**

The ornamental design for a delta deep flying wing, as shown and described.

DESCRIPTION

FIG. 1 is a top view of a delta deep flying wing according to the invention showing the new design, the bottom view being identical.

FIG. 2 is a right side view thereof; the left side view being a mirror image.

FIG. 3 is a rear view thereof; and,

FIG. 4 is a front view thereof.
